UNITED STATES PATENT OFFICE

HARRY A. PALMER, OF BOSTON, MASSACHUSETTS, ASSIGNOR TO PALMER INVENTIONS,
INCORPORATED, A CORPORATION OF MASSACHUSETTS

PUMP MECHANISM

Application filed April 29, 1932. Serial No. 608,330.

This invention relates to a pump mechanism designed primarily for supplying fuel to the combustion chamber of an internal combustion engine, but it is to be understood that a pump mechanism, in accordance with this invention may be employed in any connection for which it is found applicable, and the invention has for its object to provide, in a manner as hereinafter set forth, a mechanism of the class referred to so constructed and arranged whereby its intake action for the fuel will be had on the compression stroke of the engine and the expelling action of the pump for injecting the fuel into the combustion chamber of the engine will also be had on and before the completion of the compression stroke of the engine.

A further object of the invention is to provide, a pumping mechanism for the purpose set forth, including a plunger element, acting to seal the intake to and outlet from the plunger chamber of the pump until the start of the compression stroke of the engine thereby preventing leakage and siphoning of oil during the other cycles of the engine.

A further object of the invention is to provide, in a manner as hereinafter set forth, a mechanism of the class referred to including an oil expelling plunger acting to instantly cut off the fuel to the plunger chamber at the expiration of the expelling action of the plunger.

A further object of the invention is to provide, in a manner as hereinafter set forth, a pumping mechanism having its operation for intaking fuel thereto for expulsion to the combustion chamber of the engine, so timed to prevent the fuel intaking operation of a combined fuel intaking and fuel expelling plunger until the piston of the engine starts up on its compression stroke.

To the above ends essentially and to others which may hereinafter appear, the invention consists of such parts, and such combination of parts which fall within the scope of the invention as claimed.

The pumping mechanism as hereinafter more specifically referred to is similar to that disclosed in my co-pending application, Serial Number 608,329, filed April 29, 1932.

In the drawings:

Figure 1 is a lengthwise sectional view of a fuel pumping mechanism in accordance with this invention illustrating the plunger of the mechanism in fuel intaking position. 55

Figure 2 is a section on line 2-2 Figure 1.

Figure 3 is a sectional view taken at right angles to Figure 1.

Figure 4 is a section on line 4-4 Figure 3.

Figure 5 is a fragmentary view in section 60 on line 5-5 Figure 6.

Figure 6 is a view similar to Figure 1, illustrating the plunger of the mechanism at the end of its expelling stroke.

Figure 7 is a fragmentary view in section 65 on line 7-7 Figure 6.

Referring to the drawings, 1 indicates a pump casing open at its top and formed with a bottom 2 provided with a central enlarged opening 3. Extended from casing 1 is a pair 70 of spaced parallel arms 4, 5, the former is provided with an opening 6 in which is arranged an eccentric bearing 7. The arm 5 has an opening 8. Supported by the arms 4, 5 and mounted therein is a throttle shaft 9, formed of an enlarged intermediate part 10 and a pair of reduced end parts 11, 12. The part 10 has one end thereof seated in opening 8. The end part 11 extends through bearing collar 7 and carries a lock ring 13. The part 12 80 has connected thereto, by the binding screw 14 a control 15 for shaft 9. The bearing 7 is keyed to part 11 of shaft 9. The purpose of bearing 7 will be presently referred to.

Seated on the open top of and extended into casing 1 is a pump body 16 formed of a centrally circular apertured head part 17 and a cylindrical guide part 18, the former being of a width greater than the diameter of and integral at its inner end with the latter. The wall of the aperture or inner side of part 17 is upon two different diameters. That portion of the inner side of part 17 of greatest inner diameter is indicated at 19 and that portion of smallest inner diameter at 20. 95 The portion 19 is of less length than portion 20, and opens at the outer end of the head part 17. The providing of the inner side of part 17 of two different diameters forms an internal shoulder or seat 21. The portion 19 100

of the inner side of part 17 is threaded. The inner diameter of part 18 is uniform throughout and is the same as and forms a continuation of the portion 20 of the inner side of part 17. The latter is rabbeted on its outer side, as at 22 to provide for part 17 to seat on the outer end edge of and extend into the casing 1. The pump body 16 is secured to casing 1 by holdfast devices 23. A part of 5 the portion 20 of the inner side of part 17 and the entire inner side of part 18 provides a chamber 24 for a combined fuel intaking and fuel expelling reciprocatory plunger 25 which has a snug sliding fit with the wall of 10 chamber 24. The latter is open at its inner end and closed at its outer end by a peripherally threaded and shouldered plug 26 formed with a port 27 extending from the inner end of and opening into a valve pocket 15 28 formed in the plug intermediate its ends. The plug 26 is formed with an annular opening 29 of greater diameter than and which opens at its inner end into pocket 28. The outer end of opening 29 communicates with a 20 cavity 30 formed in the outer end of plug 26. The wall of opening 29 is threaded. The plug 26 has a reduced inner part 26' which extends into the portion 19 of the inner side of part 17 of pump body 16. The peripheral 25 shoulder of the plug engages a packing 26" mounted on seat 21. The threads of the plug engage with the threaded portion 19 of the inner side of the pump body 16. The plug 26 extends outwardly from the latter.

Secured to the wall of opening 29 is a tubular coupling member 31 formed of an intermediate, an outer and an inner part 32, 33 and 34 respectively. The part 32 is of greater diameter than parts 33, 34. The part 33 40 is of greater outer diameter than part 34. The inner diameter of parts 32, 33 is the same, but of less diameter than the inner diameter of part 34. The parts 33, 34 are peripherally threaded. The part 34 engages with the wall 45 of opening 29 and has its inner diameter the same as the diameter of pocket 28. Part 32 is arranged within and extends from cavity 30. At the point of mergence of part 34 with part 32, a valve seat 35 is formed for a ported 50 valve 36 of T-shape cross section. Arranged within part 34, surrounding the stem of valve 36 and interposed between the head of the latter and a check valve 37 is a controlling spring 38. The valve 37 is normally arranged in pocket 29. The stem of valve 36 is spaced from valve 37 and constitutes a stop for the arresting of the opening movement of the latter. Extended into the outer end of part 33 is a fuel conducting pipe 39 55 which leads to an ejector nozzle, not shown, for extension into the combustion chamber, not shown, of the engine. A packing 40 surrounds pipe 38 and is seated on the outer edge of part 33. A packing gland 41 surrounds 60 pipe 39, encloses packing 40 and threadedly

engages with the periphery of part 33.

The part 17 of the pump body 16 is formed with a horizontally disposed fuel intake chamber 42 which is shallow and gradually increasing in width from its outer open end to its inner end wall. The chamber 42 is disposed at right angles to chamber 24 and has its top wall 43' below and in very close proximity to the inner end of plug 26. The bottom wall 44 of chamber 42 is arranged in close proximity to the inner end of plug 26. Communication is had between the chamber 42 and the upper end of chamber 24 by a series of spaced ports 45 in the wall 43. The arrangement is such that when the plunger 25 moves inwardly about .006 of an inch, the intake from chamber 42 to chamber 24 starts. The part 17 of pump body 16 is formed with a circular opening 46 having the wall thereof threaded for securing thereto a fuel supply nozzle 47. The opening 46 communicates with the open outer end of chamber 42 and nozzle 47 likewise. The nozzle 47 comprises a tubular body portion 48 having an enlarged outer part 49 and a reduced inner part 50, the latter being peripherally threaded to secure it to the threaded wall of opening 46. Arranged within part 49 is a collar 51 carrying a valve stop 52. Positioned in part 49 and bearing against the outer end edge of collar 51, is a sleeve 53, having its inner end formed with a valve seat 54. The outer end 55 of sleeve 53 is beveled. Slidably mounted in sleeve 53 is the stem of a check valve 56 which coacts with the seat 54 for closing the nozzle 49 to supply and to arrest any outward expulsion of the fuel from chamber 42 from passing to the supply or feed pipe 57, which is clamped against the outer end of sleeve 53 by a tubular plug 58, mounted on pipe 57 and threadedly engaging with the inner face of part 49 at the outer end of the latter.

The plunger 25 is formed with an annular peripheral shoulder 59 for a purpose to be referred to. Surrounding and extending inwardly from the part 18 of the pump body 16, is a reciprocatory driver 60 for the plunger 25, and which acts upon the latter to provide its fuel expelling stroke. The driver 60 coacts with the shoulder 59. The driver 60 includes a sleeve 61 formed at its outer end with an outwardly directed annular flange 62, and at its inner end with an inwardly directed annular flange 63. The latter is arranged inwardly with respect to and is adapted to abut against shoulder 59 to impart to the plunger 25 a fuel expelling stroke. The sleeve 61 encompasses part 18. The driver 60 is arranged in casing 1 and is of a diameter to pass through opening 3 on its inward movement. The driver 60 also provides a compressing means for an actuating spring 64 therefor. The spring 64 encompasses sleeve 61 and is interposed between flange 62 and the bottom 2 of casing 1.

The inner portion 65 of plunger 25 is reduced and formed with an opening 66 through which extends a headed pin 67 provided with a locking ring 67'. Carried by 5 the pin 67, at each side of portion 65 of plunger 25, are abutment members 68 each having a flat working surface 69.

Pivottally mounted on part 11 of shaft 9, is a pawl 70 for shifting plunger 25 inwardly 10 to provide for driver 60 to compress spring 64. The pawl 70 includes a centrally apertured intermediate part 71, an outer end part 72 formed with a depending nose 73, and a bifurcated inner part to form a pair of spaced 15 arms 74 for straddling the portion 65 of plunger 25. The arms 74 have flat working surfaces 75 for seating upon the working surfaces 69 of the abutment members 68. The arms 74 are maintained against surfaces 69 20 by a retaining spring 76 which surrounds the inner portion of plunger 25 and is interposed between flange 63 and the upper edges of arms 74.

Arranged adjacent to and below shaft 9 25 is a stationary shaft 77 mounted in supports 78, 78' and having a peripheral combined stop and spacing boss 79 in proximity to one end. The support 78 carries a combined spacing and stop sleeve 80. Revolvably 30 mounted on shaft 77 between boss 79 and collar 80 is a cam operating shaft 81. The cam, indicated at 82 is integral with shaft 81 at one end of the latter. Integral with the other end of shaft 81 is a peripheral collar 35 83 encompassed and driven from a driver 84, which is connected to and operated from any suitable means, not shown, actuated from the engine. The arrangement is to be such that shaft 81, cam 82, collar 83 and driver 84 will 40 revolve together bodily, except when the engine back-fires and causes the driver to operate reversely.

The driver 84 is formed with a pocket 85. The collar 83 is cut out on one side, as at 45 86 to provide a shoulder 87. Arranged within pocket 85 and engaging the shoulder 87 is a spring controlled latch 88 which couples the collar and driver 84 together to provide for the bodily movement referred to. When 50 the engine backfires and reverses, the movement of driver 84, the cam shaft 81 remains stationary, until the driver 84 operates in its normal direction and the latch 88 engages shoulder 87.

55 The cam 82 is formed with a pair of oppositely disposed working surfaces 89, 90 which gradually rise and terminate into a pair of oppositely disposed lobes 91, 92.

The nose 73 of pawl 70, travels successively 60 upon the surfaces 89, 90 from the low part to the high part of the latter, whereby the pawl 70 is shifted on its shaft 9, in a manner to lower the arms 74 thereof, until the nose 73 clears the lobes and drops upon the 65 low parts of the surfaces 89, 90. When the

pawl 70 is shifted to lower its arms 74, the latter bearing against the members 68, will shift the plunger 25 inwardly to open the fuel intake chamber 42 to the chamber 24 drawing fuel into the latter forwardly of 70 plunger 25. When the latter is moved inwardly, the shoulder 59 bearing against flange 63, will carry driver 60 therewith compressing spring 64. Upon the nose 73 clearing a lobe the driver 60 will be released and 75 spring 64 acting upon the latter will project driver 60 outwardly, which carries the plunger 25 therewith and provides the fuel expelling stroke for the latter.

The foregoing operation is to be carried 80 out during the compression stroke of the engine and the mechanism is so connected with the engine to provide for its operation at the period as referred to. The plunger 25, after 85 its fuel expelling stroke will be held tightly against plug 26 by springs 64 and 74 to prevent leakage and also close ports 45. The port 27 in plug 26 provides the outlet for chamber 24.

The control shaft 9 in connection with 90 bearing 7 permits for adjusting the stroke of the pump, due to the fact that such elements provide for raising pawl 70 relative to cam 82 so that the duration of the travelling contact of the nose with the cam will vary to 95 change the operating stroke of the pump, that the travelling be short the pump stroke will be short, but if such travelling contact be long it is obvious that the stroke of the pump will be increased.

100 What I claim is:—

1. In a fuel pumping mechanism for internal combustion engines, a tubular structure having a part thereof of uniform inner diameter to provide a chamber for a fuel intake and expelling plunger, said chamber being open at its inner end, a normally closed valve controlled fuel outlet structure secured to the tubular structure and having a reduced portion extending into the outer portion and abutting the inner face of said part to provide a normally closed apertured outer wall for said chamber, said tubular structure including a valve controlled fuel intake normally closed to a source of fuel supply, said intake arranged inwardly of and in very close proximity to said wall, disposed at right angles to the latter and opening into said chamber at the extreme outer end of the latter, and an intermittently operable, 110 spring controlled, reciprocatory fuel intake and expelling plunger operating in said chamber and constituting means for simultaneously closing said intake and apertured wall to said chamber at the end of its expelling stroke and for opening said intake and apertured wall on its intake stroke. 115

2. In a fuel pumping mechanism for internal combustion engines, a reciprocatory spring controlled structure including a 120

125

130

plunger for intaking fuel into and for expelling it from said mechanism, abutment means carried by and at each side of one end of the plunger inwardly of said structure, a pivot arranged adjacent to and forwardly of said means, an actuatable pawl pivotally mounted intermediate its ends on said pivot, said pawl including a bifurcated inner part bearing against said members for intermittently imparting a fuel intake stroke to the plunger against the action of the controlling spring for said structure, said pawl having its outer end provided with a depending nose, a rotatable cam arranged outwardly with respect to said pivot and coacting with said nose to actuate the pawl in a direction for intermittently imparting a fuel intake stroke to the plunger, said driving structure including means for intermittently imparting an expelling stroke to said plunger, a coiled spring encompassing the plunger and interposed between said structure and inner part of said pawl, said pivot being adjustable for varying the stroke of the plunger, means integral with the pivot for adjusting it, and supporting means common to said pivot and adjusting means.

In testimony whereof, I affix my signature hereto.

HARRY A. PALMER.
